US00D585810S

(12) **United States Design Patent**
Van de Rostyne et al.

(10) **Patent No.:** **US D585,810 S**
(45) **Date of Patent:** ** *Feb. 3, 2009

(54) **HELICOPTER PROPELLER**

(75) Inventors: **Alexander Jozef Magdalena Van de Rostyne, Bornem (BE); Chi Pok Billy Wai, Quarry Bay (HK)**

(73) Assignee: **Silverlit Toys Manufactory Ltd., Hong Kong (HK)**

(*) Notice: This patent is subject to a terminal disclaimer.

(**) Term: **14 Years**

(21) Appl. No.: **29/283,934**

(22) Filed: **Aug. 27, 2007**

Related U.S. Application Data

(60) Continuation of application No. 29/277,652, filed on Mar. 5, 2007, now Pat. No. Des. 552,531, which is a division of application No. 29/275,322, filed on Dec. 20, 2006, now Pat. No. Des. 546,269, which is a continuation-in-part of application No. 11/462,177, filed on Aug. 3, 2006, and a continuation-in-part of application No. 11/465,781, filed on Aug. 18, 2006.

(30) **Foreign Application Priority Data**

Jan. 19, 2006 (BE) 2006/0043

(51) **LOC (9) Cl.** **12-07**

(52) **U.S. Cl.** **D12/345**

(74) *Attorney, Agent, or Firm*—Greenberg Traurig, LLP

(57) **CLAIM**

The ornamental design for a helicopter propeller, as shown and described.

DESCRIPTION

FIG. 1 is a perspective side view of a helicopter propeller; FIG. 2 is an opposite perspective side view of the helicopter propeller;

FIG. 3 is a side view of the helicopter propeller; and,

FIG. 4 is a top view of the helicopter propeller.

Broken lines are for illustrative purposes only and form no part of the claimed design.
